UNITED STATES PATENT OFFICE.

EDWARD G. HODGES, OF MARSHALLTOWN, IOWA.

AUTOMATIC AUXILIARY AIR-SUPPLY DEVICE FOR INTERNAL-COMBUSTION ENGINES.

1,301,054.

Specification of Letters Patent. Patented Apr. 15, 1919.

Application filed April 6, 1918. Serial No. 227,155.

To all whom it may concern:

Be it known that I, EDWARD G. HODGES, a citizen of the United States, and resident of Marshalltown, in the county of Marshall 5 and State of Iowa, have invented a certain new and useful Automatic Auxiliary Air-Supply Device for Internal-Combustion Engines, of which the following is a specification.

10 The object of my invention is to provide an automatic auxiliary air device adapted for use with internal combustion engines for supplying air to the fuel mixture, which device is of very simple, durable 15 and inexpensive construction and is so constructed and arranged that it may be readily and easily mounted on or removed from any ordinary explosive engine.

15 A further object is to make such a device 20 in the form of an attachment so that it may be readily adapted for use with engines of different makes.

More particularly it is my object to provide such a device including a readily adjustable air supply pipe having a flaring or bell-shaped end adapted to receive air, and provided with a butterfly valve and an engaging stop therefor, and a shield member adapted to protect one side of the butterfly 25 30 fly valve from the pressure of air blasts passing through said air supply pipe.

With these and other objects in view my invention consists in the construction, arrangement and combination of the various 35 parts of the device, whereby the objects contemplated are attained, as hereinafter more fully set forth, pointed out in my claims and illustrated in the accompanying drawings, in which:

40 Figure 1 shows a side elevation of an engine block having mounted thereon my improved automatic auxiliary air supply device.

Fig. 2 shows an enlarged, vertical, sectional view through that portion of the air supply pipe having the butterfly valve and through the chamber in which the auxiliary air and fuel mixture are mixed.

Fig. 3 shows a horizontal, sectional view 50 taken on the line 3-3 of Fig. 1; and

Fig. 4 shows a detail, plan view with parts broken away, of a part of the mixer device.

In my drawings herewith which illustrate one form in which my invention may 55 be made I have used the reference numeral 10 to indicate generally the engine block.

In front of the engine is the ordinary fan 11.

There is provided a short tubular member 12 for conducting the fuel mixture from the carburetor to the intake manifold. The member 12 is formed with annular flanges 13 and 14 at its ends. I provide an extra tube 15 for receiving the tube 12 and in which the flanges 13 and 14 fit snugly. 65

The tube 12 is provided with series of rows of small openings 16. The rows of openings 16 in the upper half of the tube 12 are preferably staggered with relation to the rows of openings in the lower half of said tube. 70

I provide also a flexible fuel conducting tube 17 having a flaring end 18 preferably located at a suitable point to receive the air from the fan 11 and the air rushing in 75 through the radiator.

Connected with the tube 15 is a short tube 19. An intermediate tube 20 is screwed to the ends of the respective tubes 19 and 17, as shown in Fig. 2. Received within the tube 20 is a butterfly valve 21. It will thus appear that the tube 20 forms a valve casing. 80

Within the valve casing 20 is a stop 22 for limiting the movement of the valve 21 in one direction. 85

The stop 22 forms a seat for the valve 21 for approximately one-half the circumference thereof. The valve casing 20 is provided with a row of small holes 23 near the valve 21 when the latter is closed on the side thereof next to the intake end of the valve casing. 90

Within the valve casing 20 is an inclined shield 24 for protecting that half of the valve 21 which coacts with the seat 22, from contact with a current of air passing through the air supply pipe 17 from the flaring end thereof, and for guiding the air and directing it against the other half of the valve. 95

It will be noted that while under normal conditions, when the engine is not running, the underside of the shield 24 is, in a sense, subject to atmospheric pressure, because air will enter the valve casing 20 through the openings 23, or through the open ended tube 17 and will pass around the upper end of the shield 24 adjacent to the valve 21, yet when the engine starts and a vacuum is created in the pipe 19, the under surface 110 of the shield 24 and the pocket formed between said shield and casing 20 is subject

substantially to the vacuum conditions in the manifold as soon as the valve 21 begins to open.

After the initial opening movement which is due solely to the air blast from the fan 11, further opening movement is due both to the force of the air blast and to the unbalanced pressures on the two sides of the upper half of the valve.

10 The valve 21 has a stem 25 on which is an arm 26. Connected with the arm 26 is a spring 27 for normally holding the valve 21 seated or closed.

It will be seen that my device comprises 15 an attachment in which the tubes 12 and 15 are inserted between the carburetor and intake manifold and the other parts are connected therewith in the manner hereinbefore described, so that the device may be applied 20 on various makes of cars by slight alterations or adjustments.

In the practical operation of the device the spring 27 is secured in position so as to hold the valve 21 seated until certain 25 pressure occurs against the valve 21. Thereupon the pressure of air through the tube 17 will engage the unprotected side of the valve 21 and tend to open the valve. The greater the air pressure the greater will be 30 the opening movement of the valve, and the greater will be the supply of air furnished to the fuel mixture. On account of the mixing device hereinbefore described, comprising the tubes 12 and 15 it will be seen that 35 the air passing from the tube 15 through the openings 16 in the tube 12 will be thoroughly mixed with the fuel mixture.

The advantages of an auxiliary air supply device of this general nature are more 40 fully set forth in my co-pending application Serial Number 215,414.

Some changes may be made in the construction and arrangement of the various parts of my improved device without 45 departing from the essential features and purposes of my invention, and some changes will be made in adjusting the device for use with different cars, and it is my intent to cover by my claims any modifications of 50 structure or use of mechanical equivalents which may be included within the scope of said claims.

It will readily be seen that the spring 27 may be located at different places for 55 accomplishing the purpose, and that other changes might be made.

It will be obvious with this device, that the warm air and vapors for fuel mixture

must be arranged for through the regular carburetor air intake. 60

In the end of the flaring member 18 is a screen 18a for keeping dirt and the like out of the tube 17.

The holes 23 permit a movement of the air through the tube 17 even before the air 65 pressure is great enough to open the valve 21.

I have shown in Fig. 2, a small pipe 28 communicating with the pipe 19 and designed to be connected with the vacuum 70 feed tank forming part of the fuel system of a motor vehicle.

I claim as my invention:

1. An auxiliary air attachment for motor vehicle engines comprising means for conducting air to the fuel supply of such engines, said means including a tube having a flaring end, a valve casing, a butterfly valve therein, a shield for protecting a portion of said butterfly valve from contact 80 with blasts of air passing through said air supply tube to said first described tubes, means for yieldingly holding said valve in its seated or closed position, said casing being provided with openings in its wall adjacent to said valve on the side of said casing opposite said shield, and on the side of the valve adjacent to the intake end of the valve casing. 85

2. In a device of the class described, 90 means for supplying auxiliary air to the fuel mixture of an explosive engine, said means including an air supply tube, a valve casing communicating therewith, a butterfly valve mounted in said casing, a seat for 95 the edge of said butterfly valve for approximately one-half of its circumference, a shield and guide device adapted to protect a portion of said butterfly valve from contact with blasts of air passing through said 100 tube and for guiding said air against another portion of said valve.

3. In a device of the class described, a fuel mixture conducting tube, an auxiliary air supply tube arranged in communication 105 with said first tube, a valve casing arranged in the path of air passing through said air supply tube, a butterfly valve in said casing, an inclined shield for protecting substantially one-half of said butterfly valve 110 from the passing air, and for directing the passing air against the other half of said butterfly valve.

Des Moines, Iowa, March 5, 1918.

EDWARD G. HODGES.
